UNITED STATES PATENT OFFICE.

JULIUS MOHS, OF PHILADELPHIA, PENNSYLVANIA.

GAS-ENGINE.

SPECIFICATION forming part of Letters Patent No. 426,297, dated April 22, 1890.

Application filed August 20, 1889. Serial No. 321,435. (No model.)

To all whom it may concern:

Be it known that I, JULIUS MOHS, a citizen of the United States, residing in the city and county of Philadelphia, State of Pennsylvania, have invented a new and useful Improvement in Gas-Engines, which improvement is fully set forth in the following specification and accompanying drawings.

The invention essentially consists of a gas-engine wherein the power developed by a rotating shaft actuates a sliding connection attached and operating a sliding valve to open and close gas and air inlet ports, and also to operate an exhaust-valve relatively with said sliding valve.

The invention further consists of the general construction, arrangement, and combination of the several parts, as will be more fully hereinafter set forth.

The object of the invention is to dispense with a multiplicity of parts and to thereby simplify the construction and cause a more direct application of the power as generated.

Figure 1 represents a vertical section of a gas-engine embodying my invention. Fig. 2 represents a plan view of the slide-valve and its sliding connection. Fig. 3 represents an end elevation of the valve detached. Fig. 4 represents a plan view of the sliding connection for the valve. Fig. 5 represents a side elevation of a gas-engine embodying my invention. Fig. 6 represents an end elevation of the slide-valve and connecting-slide. Fig. 7 represents an end elevation of the sliding connection. Fig. 8 represents a front view of the valve and sliding connection. Figs. 9 and 10 represent, respectively, a side and a front view of the crank for operating the sliding connection of the slide-valve. Fig. 11 represents a plan view of the swinging eccentric-rod for operating the slide-valve through the sliding connection. Fig. 12 represents a similar view of the device shown in Fig. 11, having a slightly-modified central bearing. Fig. 13 represents a side elevation of the engine, showing the slide-box in section and the slide-valve and sliding connection removed. Fig. 14 represents a horizontal section through the piston-cylinder and slide-box.

Similar letters of reference indicate corresponding parts in the several figures.

Referring to the drawings, A designates a

shaft, on which is mounted a gear-wheel C', adapted to mesh with any suitable mechanism operated by the main shaft, (not shown,) 55 and to said gear-wheel is eccentrically attached one end of a connecting-rod or pitman g', whose opposite end is eccentrically secured to a vertically-disposed bevel gear-wheel g² by a suitable crank, said wheel g² being in mesh with a horizontally-situated bevel gear-wheel g³, in connection with the shaft g⁶ of a governor g⁴. The central portion of the said pitman g' has loose bearing through or upon a suitable movable or stationary support g, as shown in Figs. 5, 11, and 12; but in all constructions it is necessary that the said pitman have a swinging movement and a sliding play on its support g. The said gear-wheel g² is mounted on a shaft g⁵, on the inner end of which is affixed a crank b, having a cam n, and on the inner face of said crank b is fixed a wrist-pin or analogous device n'. To the said device n' is attached a sliding connection a', consisting of a block or plate engaging a slide-valve a², working over ports a³ and a⁴, and an igniting-duct a⁵ in the divisional wall between a box or chamber h' and a cylinder h. The port a³ constitutes a canal or chamber, which receives the commingled 80 air and gas from the air and gas supply pipes d' and d². The port a⁴ extends through the divisional wall between the box or chamber h' and the cylinder h and forms the sole communication from the port a³ and the duct a⁵ 85 into said cylinder. The duct a⁵ contains a jet of flame for igniting the commingled gas and air to produce the requisite explosion.

The cam n of the crank b is adapted to engage and operate the upper end of a bell-crank lever b', which is connected to the stem of a valve b², said stem having a weight b³ on the lower end thereof to return the same to its seat when raised by said bell-crank lever b'. Said valve provides means of exhaust 90 for the cylinder and opens communication between the same and an escape-duct i, extending through the wall of cylinder h. The said cylinder h is surrounded by a water-jacket C to temper the same and ameliorate 95 the heated condition thereof arising from the successive explosions of the gas and air and heat generated thereby.

Within the cylinder h is mounted a piston

f, having a rod connected to a suitable crank-wheel. (Not shown.)

In operation the gas and air are drawn into the cylinder *h* through pipes *d'* and *d''* and ports *a³* and *a⁴* as the piston makes a forward stroke under accumulated momentum, and the said piston compresses the charge on the return-stroke, and then the charge is fired by the igniting-flame in the duct *a⁵*.

- 10 The mechanism operating the sliding connection *a'* and the slide-valve *a²* is so relatively timed that said slide-valve first opens communication between the gas and air port *a³* and the cylinder *h*, and then shuts off said communication and connects the duct *a⁵* with the port *a⁴* to cause an explosion of the commingled gas and air in the cylinder *h*, which reaches the flame in duct *a⁵* through port *a⁴*, to again force the piston back. After each 20 explosion the valve *b²* is raised to exhaust the cylinder *h* by means of the cam *n* on crank *b* operating the lever *b'*, as set forth. This operation becomes successive and the mechanism regularly operated thereby.
- 25 The construction of the governor mechanism, though I do not limit myself to this precise arrangement, is as follows: The cylinder *h* has standards *h²* mounted thereon, whose upper portions are tubular and joined at 30 their upper ends by a tubular yoke *h³*, having a centrally-located spring-actuated valve *h⁴*. The stem *h⁵* of said valve depends adjacent to the sleeve *g⁷* on the governor-shaft *g⁶*, and the said valve, being controlled by a 35 spring, is opened or closed as the sleeve *g⁷* rises or falls on the said shaft *g⁶*, which operation is due to the movement of the governor-arms by centrifugal force. A pipe *k* connects the cylinder *h* with one of the standards *h²*, 40 and an exhaust-pipe *k'* is attached to the other standard *h²*. The said pipe *k* is supplied with a check-valve *k²*, for a purpose well understood. The slide-valve *a²* is vertically disposed and travels longitudinally of 45 the cylinder *h*, and is operated by the sliding connection *a'* held therein and moving vertically therethrough, the said connection being actuated by the wrist-pin *n'* or analogous device on the eccentric *b*. The time of

movement of said valve is such that when 50 ports *a³* and *a⁴* are connected to open into cylinder *h* the duct or port *a⁵* is closed, and when port *a⁴* and duct *a⁵* are opened into each other the duct *a⁵* is shut out from communication with the cylinder *h'*.

Having thus described my invention, what I claim as new, and desire to secure by Letters Patent, is—

1. In a gas-engine, the combination of a reciprocating valve provided with ports for the admission and ignition of the charge, a transverse guide in said valve, and a sliding connection in said guide, operated by a revolving shaft, said shaft being parallel to and operated by connection with the main engine-shaft, substantially as described.

2. In a gas-engine, the combination of a reciprocating valve for controlling the admission and ignition of the charge, a transverse guide in said valve, operated by a revolving shaft, said shaft being parallel to and operated by the main engine-shaft, and mechanism for operating a centrifugal governor directly from the revolving shaft simultaneously with the valve, substantially as described.

3. In a gas-engine, the combination of the crank *b*, having a cam *n* thereon and a wrist-pin or analogous device *n'* on one face thereof, the connecting-slide *a'*, attached to said device *n'*, and the slide-valve *a²*, substantially as described.

4. In a gas-engine, the combination of the cylinder having ports therein, a slide-valve over said ports, an actuating connecting-slide for said valve, the crank for operating said connecting-slide, an exhaust-valve opened by said crank, and the swinging pitman, substantially as described.

5. In a gas-engine, the combination of the cylinder or chamber having a piston therein and ports, a slide-valve over said ports, a sliding connection for said valve, and a swinging pitman movably mounted on a fulerum, substantially as described.

JULIUS MOHS. [L. S.]
